[57] CLAIM

The ornamental design for a hair curler steamer, as shown and described.

DESCRIPTION

FIG. 1 is a top, front, side perspective view of a hair curler steamer showing my new design;

FIG. 2 is a top plan view;

FIG. 3 is a front elevational view thereof, the rear elevational view being identical;

FIG. 4 is a bottom plan view thereof; and,

FIG. 5 is a side elevational view thereof, the opposite side being identical.

FIG. 1

FIG. 5

FIG. 2

FIG. 3

FIG. 4
